(57) **CLAIM**

The ornamental design for a bottle holder, as shown and
described.

DESCRIPTION

FIG. 1 is a front, left, and top perspective view of a first
embodiment of a bottle holder showing my new design;

FIG. 2 is a front view thereof;

FIG. 3 is a rear view thereof; the left and right side views
being identical thereto;

FIG. 4 is a top view thereof;

FIG. 5 is a bottom view thereof;

FIG. 6 is a front, left, and top perspective view thereof in
which the intermediate boxes are rotated with respect to the
top and bottom boxes, and in which the slidable lid is in an
open position;

FIG. 7 is a front view thereof;

FIG. 8 is a rear view thereof;

FIG. 9 is a top view thereof;

FIG. 10 is a bottom view thereof;

FIG. 11 is a front, left, and top perspective view of a second
embodiment of the bottle holder;

FIG. 12 is a front view thereof;

FIG. 13 is a rear view thereof; the left and right side views
being identical thereto;

FIG. 14 is a top view thereof;

FIG. 15 is a bottom view thereof;

FIG. 16 is a front, left, and top view thereof in which the top
box is rotated with respect to the bottom box, and in which the
slidable lid is in an open position;

FIG. 17 is a front view thereof;

FIG. 18 is a rear view thereof;

FIG. 19 is a top view thereof;

FIG. 20 is a bottom view thereof;

FIG. 21 front, left, and top perspective view of a third
embodiment of a bottle holder;

FIG. 22 is a front view thereof;

FIG. 23 is a rear view thereof; the left and right side views
being identical thereto;

FIG. 24 is a top view thereof;

FIG. 25 is a bottom view thereof;

FIG. 26 is a front, left, and top view thereof in which the
intermediate box is rotated with respect to the top and
bottom boxes, and in which the slidable lid is in an open
position;

FIG. 27 is a front view thereof;

FIG. 28 is a rear view thereof;

FIG. 29 is a top view thereof;

FIG. 30 is a bottom view thereof;

FIG. 31 is a front, left, and top perspective view of a first
embodiment of a bottle holder;

(Continued)

FIG. 32 is a front view thereof;
 FIG. 33 is a rear view thereof; the left and right side views being identical thereto;
 FIG. 34 is a top view thereof;
 FIG. 35 is a bottom view thereof;
 FIG. 36 is a front, left, and top view thereof in which the intermediate boxes are rotated with respect to the top and bottom boxes, and in which the slidable lid is in an open position;
 FIG. 37 is a front view thereof;
 FIG. 38 is a rear view thereof;
 FIG. 39 is a top view thereof; and,
 FIG. 40 is a bottom view thereof.
